UNITED STATES PATENT OFFICE

CHARLES R. SNYDER, OF SPOKANE, WASHINGTON.

ESCUtCHEON-PLATE.

1,112,485.

Specification of Letters Patent. Patented Oct. 6, 1914.

Application filed July 8, 1913. Serial No. 777,888.

To all whom it may concern:

Be it known that I, CHARLES R. SNYDER, a citizen of the United States, residing at Spokane, in the county of Spokane and State of Washington, have invented new and useful Improvements in Escutcheon-Plates, of which the following is a specification.

This invention relates to escutcheon or key-hole plates and the principal object of the invention is to provide a plate having means for guiding the key to the key-hole.

It is frequently difficult to locate the key-hole in an escutcheon plate, particularly on a dark night, and it is, therefore, the object of this invention to provide simple and efficient means for facilitating the insertion of the key in the key-hole.

Further objects of the invention will appear as the following description is read in connection with the accompanying drawing, which forms a part of this application, and in which:

Figure 1 is an elevation. Fig. 2 is a transverse sectional view. Fig. 3 is a vertical sectional view on the line 3—3 of Fig. 1.

Referring more particularly to the drawing, 1 represents an ordinary escutcheon plate having a key-hole 2. Leading into the key-hole are grooves 3 and 4, the latter extending vertically above the key-hole and

the former extending vertically below the key-hole. It will be, of course, understood that transverse or diagonal grooves may be employed if found to be desirable. In the structure shown with the vertically arranged grooves the key is passed across the escutcheon plate until it enters the groove and then moved either up or down until it enters the key-hole.

What is claimed is:

1. An escutcheon plate having a longitudinally extending groove of uniform diameter throughout, a key-hole formed in the walls of the groove intermediate the ends thereof, said groove being of a width slightly greater than the end of the key and adapted to guide the key to the key-hole.
2. An escutcheon plate having a longitudinally extending V-shaped groove and a key hole formed in the walls of the groove, said groove being of slightly greater width than the key hole adapted to effectively guide a key to the key hole.

In testimony whereof I affix my signature in presence of two witnesses.

CHARLES R. SNYDER.
